US0D1064773S

(12) **United States Design Patent** (10) **Patent No.:** **US D1,064,773 S**
(45) **Date of Patent:** **** Mar. 4, 2025**

(54) **HAMMER DRILL**

(71) Applicant: **Robert Bosch GmbH**, Stuttgart (DE)

(72) Inventors: **Vincent Hasenmayer**,
Stuttgart-Möhringen (DE); **Kay Zass**,
Esslingen (DE)

(73) Assignee: **Robert Bosch GmbH**, Stuttgart (DE)

(**) Term: **15 Years**

(21) Appl. No.: **29/908,066**

(22) Filed: **Jan. 11, 2024**

Related U.S. Application Data

(63) Continuation of application No. 29/864,538, filed on
Jun. 3, 2022, now abandoned.

(57) **CLAIM**

The ornamental design for a hammer drill as shown and
described.

DESCRIPTION

Cross reference is made to copending U.S. design patent
application Ser. No. 29/864,537 entitled "Hammer Drill" by
Hasenmayer et al., which was filed on Jun. 3, 2022.

FIG. 1 is a perspective view of a hammer drill showing our
new design;

FIG. 2 is a left side elevational view of the hammer drill of
FIG. 1;

FIG. 3 is a right side elevational view of the hammer drill of
FIG. 1;

FIG. 4 is a front elevational view of the hammer drill of FIG.
1;

FIG. 5 is a rear elevational view of the hammer drill of FIG.
1;

FIG. 6 is a top plan view of the hammer drill of FIG. 1; and,
FIG. 7 is a bottom plan view of the hammer drill of FIG. 1.
The dashed broken lines shown in the drawings depict
portions of the hammer drill that form no part of the claimed
design.

1 Claim, 7 Drawing Sheets
